UNITED STATES PATENT OFFICE.

PAUL F. WOLLENWEBER, OF TOLEDO, OHIO, ASSIGNOR, BY MESNE ASSIGNMENTS, TO THE ELECTRIC AUTO-LITE COMPANY, OF TOLEDO, OHIO, A CORPORATION OF OHIO.

IGNITION DEVICE.

Application filed June 25, 1917. Serial No. 176,733.

This invention relates to improvements in ignition devices for motor vehicles.

The principal object of this invention is to provide a single, compact device of the character indicated which is not only satisfactory for the purpose intended but has certain of the separate parts thereof constructed along novel lines having inherent advantages in such separate parts or parts per se, as well as in the assembled combination.

A further object of this invention is to provide an improved general assembly of igniter including mounting for the interrupter plate, of such a nature as to avoid the use of screws or other removable fastening means.

A further object of this invention is to provide an improved mounting for the interrupter cam of such a nature as to permit the ready adjustment of the cam relative to the drive shaft.

A further object of this invention is to provide an improved interrupter lever which is of very light weight so that it will respond quickly to the cam and give a clean, sharp make and break in the circuit.

Still a further object of this invention is to provide an improved mounting for the rotatable distributor head, by means of which the head can be very readily removed whenever desired.

Further objects of this invention relate to economies of manufacture and details of construction as will hereinafter appear from the detailed description to follow. I accomplish the objects of my invention in one instance by the devices and means described in the following specification, but it is evident that the same may be varied widely without departing from the scope of the invention as pointed out in the appended claims. A structure constituting one embodiment of my invention, which may be the preferred, is illustrated in the accompanying drawings forming a part hereof, in which:

Fig. I is a view in side elevation of a device embodying my invention.

Fig. II is a top plan view of the device with the distributor cap and rotatable distributor head removed.

Fig. III is an enlarged, sectional view,

taken substantially on the lines III—III of Fig. II.

Fig. IV is a transverse, sectional view, taken substantially on the line IV—IV of Fig. III.

Fig. V is an enlarged, detail, sectional view, showing the mounting of the interrupter plate.

Fig. VI is a detail, perspective view of one of the springs for holding the interrupter plate against the bottom of the interrupter chamber.

Fig. VII is an enlarged fragmentary, detail, sectional view, taken substantially on the line VII—VII of Fig. II.

Fig. VIII is a plan view of the blank from which the interrupter lever is formed.

Fig. IX is a detail, perspective view of the spring washer used in connection with the mounting of the lever for actuating the interrupter plate.

Fig. X is a fragmentary, detail, sectional view taken substantially on the line X—X of Fig. III.

In the drawings, similar reference numerals refer to similar parts throughout the several views, and the sectional views are taken looking in the direction of the arrows at the ends of the section lines.

Considering the numbered parts of the drawings, my improved ignition device comprises a casing 10, having a central downwardly extending stem 11, and provided with an interrupter chamber 12, and a condenser chamber 13, which is separated from the interrupter chamber by means of partition wall 14. The casing 10 is open at the top and a removable flanged ring 15 seats on the upper edge of said casing. The removable distributor cap 16, carrying the central distributor contact 27, and the distributor contacts 28 arranged toward the edge thereof, is removably secured on said flanged rim 15 by means of fastening hooks 31, which are pivotally connected at 32 to the side of the casing and engage notches 30 in said distributor cap. A drive shaft 17 is journaled in the stem 11 of the casing, said shaft being provided with an annular flange 18 engaging the bottom of the interrupter chamber 12.

The shaft is provided with a tapered upper

end 19, and the interrupter cam has the cam portion 20, provided with a tapered socket in which the tapered end 19 of the shaft is adapted to fit, and a cylindrical upper end 21, as shown in Figs. III and X of the drawings. A screw 22 is disposed axially of said cam and threaded into the upper end of the shaft 17 so as to secure said cam to said shaft. It will be seen that, by releasing the screw 22, the cam can be rotated relative to the shaft, so as to provide for an easy adjustment of the cam whenever desired.

A slot 23 is formed in the cylindrical portion 21 of the cam and the rotatable distributor head 24, which is made of suitable insulating material, carries a key 25 which fits in said slot 23, so that the rotatable distributor head rotates with the cam 20. The distributor head carries a spring metal contact piece 26, secured thereto, which contacts with the central contact 27, which is connected in the ignition circuit. The distributor head also carries the contact piece 29 in electrical connection with the contact piece 26, which is adapted to make a contact successively with each of the contacts 28, as the distributor head rotates.

A cylindrical boss 33 is formed in the bottom of the interrupter chamber 12, axially thereof, and the interrupter plate 34 is provided with a central opening, fitting said cylindrical boss, and is mounted for rotation in the bottom of the interrupter chamber. Segmental plates 35 and 36 are secured to the side wall of the interrupter chamber, the lower edge of each plate being spaced slightly from the bottom of said chamber so as to provide ledges, beneath which the edge of the interrupter plate may move, as shown in Fig. V. The plate 34 carries a pair of bow springs 37, provided with down-turned ends 38, which fit in notches 39 provided in the interrupter plate at the edge thereof, so that when the interrupter plate is in position with its edge disposed beneath the ledges formed by the plates 35 and 36 respectively, said springs 37 will engage the lower edges of said plates 35 and 36 and yieldingly hold said plate against the bottom of the interrupter chamber. A notch 40 is provided in the edge of the interrupter plate 34, which notch is of substantially the same length as the plate 35, so that the interrupter plate may be removed by rotating it to bring said notch in line with the plate 35, as will be herein-after pointed out.

A bracket 42 is mounted on the interrupter plate, being insulated therefrom by a strip 43 of insulating material, and said bracket has an upstanding arm 44, in which the contact 45 is adjustably mounted, said contact being preferably made of some hard metallic substance, such as an iridium alloy. The contact 45 is provided with the thread-

ed end 46, threaded into the arm 44 and fastened with reference thereto by means of lock nut 47, as clearly shown in Fig. VII of the drawing. A terminal having a threaded portion 48, extends through a slot 70 49 in the interrupter plate 34, and through a corresponding slot provided in the bottom wall of the casing 10, said terminal having a cylindrical stem 50.

The terminal is secured in place by the nut 51, threaded on to the threaded portion 48 and clamping the terminal to the bracket 42.

Interrupter lever 53 is pivotally mounted on the pin 52, carried by the interrupter plate 34, and a spring 54 is provided, one end of which engages the interrupter lever 53, while the other end engages the pin 55 carried by the interrupter plate, so that such spring tends normally to throw said interrupter lever so as to hold the contacts in engagement with each other. The interrupter lever is preferably made from a sheet metal blank, of the form shown in Fig. VIII, said blank 56 being triangular 90 in form and provided with openings 57, at the corners of the base of said triangular blank, and with an opening 58 at the apex thereof. A central elongated slot 59 is formed in said blank, and ears 60 are also 95 provided in line with said slot. The blank is folded to form a U-shaped channel and a block 61, of fibre or other insulating material, is inserted in said channel and secured in place therein by means of the ears 60, which are folded over as shown in Fig. VII. The block 61 has a portion 64, which projects through the slot 59 of the interrupter lever, and is adapted to be engaged by the cam 20 to vibrate said lever. The pin 52, on which the lever is fulcrumed, passes through the alined openings 57 and a contact 62 has its stem 63 mounted in the opening 58 of the lever, as shown in Fig. VII, said contact being disposed so as to engage the contact 45 mounted on the bracket 42.

A slot 65 is provided in the interrupter plate 34 and the pin 66 carried by the lever 67 extends through a slot 69, provided in the bottom of the casing 10, and has its upper end disposed in the slot 65 of the interrupter plate. The lever 67 is fulcrumed on a pin 68 carried by the bottom of the casing 10, so that, by oscillation of the lever 120 67, the interrupter plate may be rotated in the casing 10. A spring washer 70 of a peculiar form is used in order to hold the lever 67 on the pivot pin 68, said washer being shown in Fig. IX and comprising a 125 rectangular sheet of metal, slightly bowed and provided, at the corners thereof, with the up-turned fingers 71, which engage on either side of the lever 67, said washer being provided with a central opening 72 130

through which the pin 68 passes. Said washer is slipped over the end of the pin 68, with the ears 71 engaging the sides of the lever 67, and a cotter pin 73 is passed through the end of the pin 68, the bow shape of said washer tending to yieldingly force the lever into engagement with the bottom of the casing 10.

Condenser 74 is mounted in the condenser chamber 13 of the casing 10 and is provided with a pair of contact arms 75, which are supported from the side walls of the casing by means of the block of insulating material 76, and which have end portions 77, the shorter one of which is hidden by the longer, extending laterally into the casing so as to engage the cylindrical stem 50 of the terminal.

From the description of the parts given above, the operation of this device should be very readily understood. As the shaft 17 rotates, the distributor head 24, which is secured thereto so as to rotate therewith, successively establishes a circuit between the central contact 27 and each of the contacts 28, mounted on the distributor cap 16, so as to successively send a current to each of the spark plugs of the engine. Distributor cap 16 may be very quickly removed by loosening the hooks 31, and the distributor head 24 may then be removed by lifting it from the end of the stem 21 of the cam 20. The screw 22 secures the cam 20 on the upper end of the shaft 17 so that it rotates therewith and as this cam rotates, it intermittently actuates the lever 53, so as to separate the contacts 45 and 62 to break the circuit at that point. The interrupter lever, being made of sheet metal, is very light and has very little momentum of its own, so that it responds quickly to the action of the cam and does not tend to lag when the cam is rotating at a high speed. The result is that a quick and precise make and break of the circuit is secured. The interrupter cam 20 is so mounted on the end of the shaft 17, that it can be very quickly and readily adjusted relative thereto, by loosening the screw 22 and turning the cam 20 on the upper tapered end portion 19 of the shaft 17.

Interrupter plate 34 is rotably mounted in the bottom of the interrupter chamber 12 and no screws are used in fastening this device in place. In order to remove the interrupter plate the terminal 48 and the lever 67 are removed, and the interrupter plate can then be rotated so as to bring the notch 40 in line with the plate 35, when the interrupter plate 34 can be lifted out of the casing, carrying with it the interrupter lever and the bracket 42 carrying the contact 45. The interrupter plate is held in place in the bottom of the casing by the engagement of the edges thereof beneath the lower edges of plates 35 and 36, and the springs 37 yield-

ingly hold the interrupter plate in its position in the bottom of the casing due to their engagement with the lower edges of the plates 35 and 36.

As the lever 67 is turned on the fulcrum 68, the pin 66, engaging in the slot 65 of the interrupter plate, imparts a rotative movement to said interrupter plate, so that the interrupter lever is moved relative to the cam 20 to advance or retard the spark. The condenser 74 is compactly housed in the main casing with the interrupter and distributor, and it will be seen that the condenser is thus enclosed within a waterproof casing and is out of the way so that space is economized and a more compact and lighter structure is secured. In order to provide for the necessary connection between the whole of or a part of the condenser and the ignition circuit, the arms 77 are provided which engage the stem 50 of the terminal 48.

While I have described my invention in more or less detail and as being embodied in certain precise forms I do not desire or intend to be limited thereto, as on the contrary my invention contemplates broadly all proper changes, as well as the omission of immaterial elements and the substitution of equivalents therefor, as circumstances may suggest or necessity render expedient.

Having thus described my invention, what I claim as new and desire to secure by Letters Patent is—

1. In a device of the class described, the combination of a fixed contact; a suitably pivoted interrupter lever, carrying a contact co-operating with said fixed contact, said lever being formed from a sheet metal blank bent to channel-shaped form, and provided with ears thereon, a block of insulating material secured in said lever by means of said ears, which are turned inwardly to hold said block in place, and an actuating cam for said interrupter lever, said lever being provided with a slot and said block of insulating material having a portion projecting through said slot in position to be engaged by said cam.

2. In a device of the class described, the combination of an interrupter lever formed from a substantially triangular blank of sheet metal, provided with openings in the corners thereof, and having an elongated slot in the central portion thereof, and an ear on each side in line with said slot, said blank being folded to form a channel U-shaped in cross section an insulating block adapted to fit in said U-shaped channel, having a portion projecting through the slot in said folded blank of sheet metal, and the ears of said folded blank being inturned to engage the rear face of said block of insulating material to hold it in place; a contact carried in the opening in the apex of said triangular blank; and a pivot pin passing

through the aligned opening formed in the base corners of said triangular blank.

3. In a device of the class described, the combination of a casing having an interrupter chamber; a cylindrical boss provided in the bottom of said chamber; an interrupter plate rotatably mounted in the bottom of said chamber and journaled on said cylindrical boss; ledges formed on one side wall of said chamber beneath the lower edges of which the edge of said plate is adapted to engage, said plate being provided with a slot at the edge thereof of substantially the length of one of said ledges; and a pair of bow springs having down-turned ends disposed in notches in the edge of said plate, and having their body portions adapted to engage the lower edges of said ledges to yieldingly hold said plate against the bottom of said chamber; means for rotating said plate; an interrupter lever mounted on said plate; and means for vibrating said lever.

4. In a device of the class described, the combination of a casing, having an interrupter chamber, provided with a central cylindrical boss; an interrupter plate, rotatably mounted in said casing and having a central opening in which said boss is disposed, said plate being provided with a peripheral notch; ledges provided on the side wall of said casing, of substantially the same length as said notch, the edge of said plate being adapted to be disposed and to move between said ledges and the bottom of said chamber; spring means engaging the bottom edges of said ledges and yieldingly holding said plate in engagement with the bottom of said chamber; a fixed contact carried by said plate; an interrupter lever carried by said plate having a contact co-operating with said fixed contact; a shaft, carrying an interrupter cam, passing through an opening provided in said boss; and means for moving said plate in said casing.

5. In a device of the class described, the combination of a shaft, having a tapered upper end; an interrupter cam comprising a cam portion and a cylindrical portion, said cam portion having a tapered socket adapted to engage the tapered end of said shaft; an axially extending screw securing said cam to the end of said shaft, the cylindrical portion of said cam being provided with a slot; and a distributor head removably mounted on said cylindrical portion and having a key disposed in said slot.

6. In a device of the class described, the combination of a shaft having a tapered upper end; a cam comprising a cam portion, having a socket adapted to fit the tapered end of said shaft, and a cylindrical portion; a screw extending axially of said cam into the tapered end of said shaft, to hold said cam and said shaft in engagement with the

tapered end of the shaft disposed in said tapered socket; and a distributor head removably mounted on the cylindrical portion of said cam to rotate therewith.

7. In a device of the class described the combination of a shaft having a tapered end, a cam having a tapered socket adapted to fit over said end and be adjustably rotatable thereon said cam having an integral extension thereon adapted to carry a distributor arm and means extending axially of said cam and extension for securing said cam to said shaft.

8. In a device of the class described the combination of a shaft having a tapered end portion, a cam having a tapered socket to receive said tapered end portion and to permit rotative adjustment thereon, said cam having an integral, axial extension for carrying a distributor arm and a securing screw extending axially of said cam into the end of said shaft.

9. In a device of the class described, an interrupter lever comprising a channel-shaped sheet metal body provided with pivot openings at one end, a contact at the other end of said body, and an intermediate cam engaging member between the sides of said body, said sides having portions bent inwardly and compressed against the cam engaging member to hold the same rigidly in contact with the channeled back of the body.

10. A blank for ignition interrupter levers, comprising a plate of substantially triangular formation having a rectangular slot adjacent the center of the plate, and projecting holding lugs on opposite sides of said plate in line with said slot.

11. In a device of the class described, an interrupter lever comprising a channel-shaped sheet metal body provided with pivot openings at one end and a contact at the other end of said body; and an intermediate cam engaging member between the sides of said body, said sides having portions adapted to hold said cam engaging member rigidly in said channel-shaped body between the sides thereof.

12. In a device of the class described, an interrupter lever comprising a channel shaped sheet metal body provided with pivot openings at one end and a contact at the other end of said body; and an intermediate cam engaging member between the sides of said body, said sides having portions integral therewith for locating said member in a position on said lever with said sides juxtaposed against the side of said lever.

13. In a device of the class described, an interrupter lever comprising a channel-shaped sheet metal body provided with pivot openings at one end and a contact at the other end of said body; and an intermediate cam engaging member located between the sides of said body and lengthwise thereof,

said sides adapted to hold said cam engaging member rigidly in contact with the channel-shaped body.

14. In a device of the class described, an interrupter lever comprising a channel-shaped sheet metal body provided with pivot openings at one end and a contact at the other end of said body; and an intermediate

cam engaging member between the sides of said body, said sides having portions adapted to hold the cam engaging member in a pre-determined position in said channel-shaped body between said pivoted ends and said contact end.

In testimony whereof I affix my signature.
PAUL F. WOLLENWEBER.

DISCLAIMER

1,669,888.—*Paul F. Wollenweber*, Toledo, Ohio. IGNITION DEVICE. Patent dated May 15, 1928. Disclaimer filed March 23, 1936, by the assignee, *The Electric Auto-Lite Company*.

Hereby enters this disclaimer to that part of the thing patented which is claimed in claims 9 and 11 of said patent.
